EXEMPLARY CLAIM

In combination with a ground-to-ground ordnance missile having a predictable trajectory during which the missile attains a supersonic velocity, improved means for obtaining an activating signal at a predeter-

mined altitude prior to impact and after the missile has begun to decelerate, said means comprising in combination: first and second heat-responsive probes mounted to the exterior surface of said missile such that the aerodynamic heating of said probes during missile flight are highly independent of the surface conditions of the missile and missile geometry, each probe being located at the same distance aft of the missile nose so as to be exposed to the same aerodynamic heating conditions during missile flight, said probes being so constructed that said first probe has a heat capacity which is substantially different from the heat capacity of said second probe, said probes thereby having substantially different time-temperature relationships during missile flight, the heat capacities of said probes further being chosen in conjunction with predicted values of missile velocity, ambient air density and ambient air temperature throughout the missile trajectory so that the instantaneous temperature of said probes will become equal at said predetermined altitude, and probe-responsive means within said missile connected to said probes for producing an activating signal when the instantaneous temperatures of said probes become equal, said probe-responsive means including an electronic bridge-type circuit for sensing the temperatures of said probes by sensing their resistivities.

MISSILE DEVICE RESPONSIVE TO AERODYNAMICS CONDITIONS

The invention described herein may be manufactured and used by or for the Government for governmental purposes without the payment to me of any royalty thereon.

This invention relates to an application of aerodynamic heating of ordnance missiles, and more particularly to an application of aerodynamic heating of ordnance missiles attaining supersonic speeds to perform useful functions therein.

An object of this invention is to apply aerodynamic heating to the performance of useful functions.

Another object is to apply aerodynamic heating to the performance of useful functions for ordnance missiles.

Still another object is to apply aerodynamic heating to the performance of useful functions for ordnance supersonic missiles of all types.

A principal object is the application of aerodynamic heating effects to the safety and arming of supersonic missiles of all types.

An important object is the application of aerodynamic heating effects to the safety and the arming of supersonic missiles of all types at predetermined altitudes.

Another object is the employment of a continuous signal derived from aerodynamic heating effects to accomplish safety and arming of supersonic missiles of all types.

A further object is to employ elements differing in their specific heat capacities to initiate missile safety and arming at a predetermined altitude for a prescribed trajectory for supersonic missiles of all types.

A still further object is to employ elements differing in their respective heat capacities to initiate missile safety and arming at a predetermined altitude for a prescribed trajectory for a supersonic missile independent of the missile acceleration or deceleration.

Another object of this invention is the application of aerodynamic heating effects to the fusing of ordnance missiles.

Still another object is the application of aerodynamic heating effects to the fusing of ordnance supersonic missiles at predetermined altitudes.

A further object is the application of aerodynamic heating effects to the fusing at predetermined altitudes of ordnance supersonic missiles of the ground-to-ground, and air-to-ground type.

A still further object is to employ elements differing in their specific heat capacities to initiate missile fusing at a predetermined altitude for a prescribed trajectory for an ordnance supersonic missile.

Still another object is to employ elements differing in their respective heat capacities to initiate missile fusing at a predetermined altitude for a prescribed trajectory for a free-falling supersonic missile of the ground-to-ground and air-to-ground type.

An important object of this invention is the application of aerodynamic heating, to the continuous measurement of instantaneous altitudes and speeds of an ordnance missile.

Another object is the application of aerodynamic heating to the continuous measurement of instantaneous altitudes and speeds of an ordnance missile at supersonic speed.

Still another object is the continuous measurement of instantaneous altitudes and speeds for missile intelligence and telemetering.

A further object is to provide the constituent discriminatory elements that comprise the above objects singly or in any combination with employment of a single pair or several pairs of temperature sensitive probes.

Briefly, this invention is based on the fact that missiles, attaining supersonic speeds, will experience temperature changes during flight. Two temperature-sensitive probes having respectively different heat storage capacities, when subject to the same aerodynamic heating conditions, will yield distinctly different time-temperature curves. Load means are coupled with the probes to interpret aboard the missile, or to telemeter, signals obtained from the probes, or to respond to a predetermined signal therefrom to accomplish a useful function at a selected altitude or velocity for a missile.

20 The specific nature of the invention as well as other objects, uses and advantages thereof will clearly appear from the following description and from the accompanying drawing, in which:

FIG. 1 is a graphical representation of a free-fall, supersonic, ground-to-ground missile's altitude and the variations in temperature of the probes of the invention as a function of time for an exemplary trajectory.

FIG. 2 is a schematic diagram of a system contemplated by the present invention.

FIG. 3 is a plan view of a portion of a missile incorporating a possible mounting for one of the probes of this invention with certain parts broken away.

Those familiar with ordnance missiles are aware of the aerodynamic heating effects on missiles during missile flight, especially those missiles attaining supersonic speeds. This invention applies these heating effects to accomplish useful functions, and will be explained in detail with reference to a free-falling ground-to-ground ballistic missile which attains supersonic speeds. It will be understood, however, that the invention is not necessarily limited to such missiles.

It has been found that on descent free-falling supersonic missiles will experience decreasing acceleration and ultimately deceleration because of an increase in atmospheric density amongst other factors. As a result of this deceleration, the aerodynamic heating effects will be reduced so that the missile may even start to cool. Two probes of different heat storage capacities exposed to the same aerodynamic heating conditions will yield distinctly different time-temperature curves. A probe with a small heat capacity will have temperature values approximating those of the missile recovery temperatures and consequently will tend to cool at substantially the same time and at the same rate as the recovery temperature. The instantaneous recovery temperature is the temperature that would be obtained by a thermally insulated missile if the instantaneous aerodynamic heating conditions were continued over a sufficient interval of time. Additional descriptions, considerations and measurements of recovery temperature may be found in National Advisory Committee for Aeronautics, Technical Note 3623, March 1956. However, a second probe having a higher heat capacity exposed to the same aerodynamic heating will change in temperature less rapidly. Thus, at the time the recovery temperature begins to decrease, the temperature of the probe with the smaller heat capacity is much higher

than the temperature of the other probe because of the latter's relatively slow response to aerodynamic heating. In fact, when the probe with the smaller heat capacity begins to cool, the probe with the higher heat capacity is still undergoing a temperature increase but will cool shortly thereafter.

Referring now to FIG. 1, a plot of a missile's trajectory from launch to missile impact is presented by the solid line 10 as a function of altitude versus time. As will be apparent from the above taken in conjunction with FIG. 1, the two probes will heat during the major portion of missile trajectory and will cool during terminal portion of missile flight at respectively different rates. Line 11 shows the recovery temperatures of a ground-to-ground missile as a function of time. Line 12 denotes the temperatures attained by the lower heat capacity probe and line 14 temperatures attained by the higher heat capacity probe. As shown and in practice the heat capacities of the probes may be selected so that as the missile approaches the earth the temperatures of the two probes will become equal, as at T3, prior to missile impact. Furthermore, this equalization temperature T3 may selectively occur at any time during the aerodynamic cooling of the probes prior to missile impact. Accordingly, by either mathematical computation or graphical analysis, the altitude at which probe temperature equalization occurs can be predetermined, selected, or preset for particular combinations of probes for a given missile trajectory. Calculations show that the altitude at which the two probe temperatures become equal depends primarily on the values of the heat capacities of the probe. Similarly, the temperatures, the temperature differences, and rate of change of temperatures for each probe at a selected altitude may be determined. The altitude at which probe temperature equalization occurs or the probes assume definite temperatures, temperature differences or definite rates of change of temperature will be termed the fusing altitude. It will be understood that, by means of suitable schemes for measuring and interpreting the probe temperatures, various desired actions — e.g., arming or detonation — can be automatically accomplished when the fusing altitude is reached.

The deceleration of some free-falling missiles and the accompanying reduction in recovery temperatures begin at comparatively low altitudes. Therefore, for these missiles the probe temperatures must become equal shortly following the onset of the decrease in the recovery temperatures when temperature equalization determines the fusing altitude. Hence, probes having relatively low heat capacities are required. The practical lower limit for the heat capacities corresponds primarily to the practical lower limit for the probe thickness. However, it has been found, even at relatively low available fusing altitudes, heat capacities are obtainable that will result in probe cooling. Other values of heat capacities exist that will also provide a temperature reduction even though equalization of the probe temperatures may not be possible due to a limited amount of cooling that can take place in the time intervals available. Moreover, in practice it is desirable that the two probes heat and cool at significantly different rates if possible, primarily because unless the two are cooling at substantially different rates, considerations that may result in a small undesirable temperature change or error in either probe will cause a relatively large undesirable change in the fusing altitude. As the

heat capacity of a probe is increased, reduced rates of heating and cooling are obtained, and conversely, increased rates are obtained as the heat capacity decreases, hence many combinations of heat capacities of the probes may be utilized to arrive at probe temperature equalization at the same fusing altitude. Thus, by decreasing the value of the heat capacity of the probe having the higher heat capacity, both the maximum temperature attained and the temperature of this probe at the fusing altitude will be reduced. Similar results in fusing altitude may be obtained by increasing the value of the heat capacity of the probe having the smaller heat capacity.

It is desirable to select a pair of probes for which the rate of change of the difference between the two probe temperatures at the fusing altitude is approximately equal to the rate of change of the missile recovery temperature. In this case, the difference between the heat capacities is large and the fusing altitude occurs almost immediately after the maximum temperature is attained by the probe with the higher heat capacity. Similar considerations are taken into account when the fusing altitude is determined by the respective temperatures of the strips on their temperature differences or their respective rates of change of temperature for any particular altitude for a definite trajectory as will be evident to those skilled in the art.

The probes 18 and 20 may be mounted so as to form part of the exterior surface or shell of the missile proper. The probes are located at the same distance aft of the missile nose and thereby are exposed to the same aerodynamic heating conditions. Probes 18 and 20 are preferably identical except for thickness and may be suitably mounted in recessed portions in the shell of missile 16, and as such are preferably electrically and thermally insulated from the shell and exterior of missile 16.

Referring now to FIG. 2, a free-falling supersonic ordnance missile is schematically shown at 16. The relatively high heat capacity probe 18 and the relatively low heat capacity probe 20 may be positioned with respect to the missile 16 substantially as shown for schematic purposes. However, the particular location of this probe on the shell of missile 10 may be considered important. The aerodynamic heating of a missile is influenced by the type boundary layer. A turbulent boundary layer on the missile shell provides a greater aerodynamic heating than a laminar boundary layer. The boundary layer is always laminar in the immediate neighborhood of the missile nose and on proceeding towards the missile tail becomes turbulent. This transition of the boundary layer from laminar to turbulent flow is affected by such factors as the surface conditions of the missile, missile speed, and kinematic viscosity of the ambient atmosphere. Transition from a laminar to a turbulent boundary layer moves toward the missile nose as the missile descends. The surface of the shell of missile 16 forward of the probes 18 and 20 may have a roughness at least comparable to a manufacturer's painted article finish so that early transition from laminar to turbulent flow may arise at positions toward the missile nose. Then the location of the probes must be such that the type of boundary layer in the vicinity of the fusing altitude is known in order to obtain high accuracy.

Temperature-sensitive probes having the form of a cylinder with hemispherical ends may also be used.

These probes are mounted so that the aerodynamic heating of the probes would be highly independent from the surface conditions of the missile and its geometry. As illustrated in FIG. 3, (the direction of flight being in the direction of the enlarged arrow) relatively small bosses 22 may extend from missile 16 and suitably receive probes 18 and 20. Thus, in this embodiment probes 18 and 20 may assume a substantially cylindrical hemispherical configuration of suitable thickness and surface area to provide the desired heat capacities. Suitable insulation should be provided for the probes 18 and 20 from missile 16 and bosses 22 to minimize heat transfer between these parts. The heat capacities of either of the two types of probes 18 and 20 can be changed in the field without entering the missile interior by the use of a device that will serve to increase or decrease the effective thickness of the probes. For example, such a device may be a screw arrangement, the adjustment of which is accessible from the missile exterior for adding or removing lamina or solely for insertion or withdrawal of screws of the same material as probes 18 and 20, thereby increasing or decreasing the heat storage capacities of the probes. By these means, the variation of the fusing altitude for a particular combination of probes over an interval of ranges can be reduced to zero. Further, these means may serve to selectively alter the heat capacities of the probes to modify or change the fusing altitude for a specified trajectory or range.

For a given missile range, there is a family of trajectories which will obtain the desired range. Moreover, the trajectory characteristics for a given missile range may be varied by changing the missile's burning time, cut-off angle, diving angle, etc. By suitable adjustment of these parameters and others, the same fusing altitude may be obtained for a given interval of ranges. Similar considerations and factors affect fusing altitude when the latter is determinate upon other probe temperatures and the respective rates of change of temperatures of the probes.

Meteorologic conditions encountered by a missile during flight will have some effect on fusing altitude. An increase of the ambient density will tend to increase the air drag acting on the missile and thereby will reduce missile speed since the air drag is proportional to the product of the density and the square of the velocity. At high altitudes the air drag acting on a free-falling missile is initially much less than the component of the missile weight in the direction of the drag because of the small values of the ambient density. Consequently, the missile accelerates on approaching ground until the air drag and the component of the missile weight in the drag direction becomes equal. During this time, the missile attains a very high speed and the rate at which the density increases becomes correspondingly large. For this reason, the air drag acting on a missile may become several times larger than the missile's weight. Under most situations the ambient density can be predicted or calculated with a reasonable degree of certainty. However, if the actual density is not as predicted, the change in the fusing altitude due to a variation of the missile velocity accompanying a change of the ambient density has been found to be negligible for most practical applications.

For altitudes extending from sea level up to 26 miles, the ambient temperature varies between about -70° and $+90^{\circ}\text{F}$. Although the temperature-altitude relation

varies with the geographical location and the season, the temperature at altitudes below 100,000 feet may be predicted with an accuracy of within $\pm 8^{\circ}\text{F}$. This depends on the availability of temperature-altitude data along the path taken by the missile, which is usually readily obtainable. If there is a deviation between the actual and predicted ambient temperatures, again the deviation is usually harmless.

The effects of heat transmission by convection, conduction, and radiation on probes 18 and 20 may be made negligible by suitable insulation, such as air or gas seals and by proper selection of surface conditions.

The high temperatures attained by the probes 18 and 20 limit the material from which they may be formed. Materials with low melting points may not be used. Furthermore, the use of ferromagnetic material is limited to temperatures below the Curie point since it then becomes paramagnetic and the specific heat capacity changes abruptly with temperature. Since some alloys undergo a transition at a definite temperature resulting in changes in the specific heat capacity, their use is limited. Materials that oxidize at high temperatures cannot be used. In addition, the probes 18 and 20 cannot be made of any material for which the thermal conductivity is undesirably low. Examples of the materials that could be used are platinum and tantalum.

Probably the most simple and accurate method for determining the fusing altitude may be provided by comparing the electrical resistivities of the two probes 18 and 20 instead of directly comparing their temperatures. The electrical resistivity of a material is independent of the heat storage capacity and depends only — usually linearly — on its temperature. Thus no calibration of thermometers or other special temperature sensitive or interpretive devices are required.

Load means, load circuitry or electronic sensing equipment may be employed to function upon the desired signal from the probes 18 and 20 and may comprise a conventional temperature response means or circuit 24 utilizing each probe as an arm. It will be obvious to those skilled in the art that other circuits or mechanisms can be used and should be used for the many applications of the present invention. The high order of sensitivity of a bridge-type circuit may be desirable in practice because of the relatively small magnitude of the output signal derived from the difference in temperatures of the probes 18 and 20. The intelligence obtained by the probe temperature response means 24 may then be applied to trigger or energize a safety and arming mechanism 26 or any of a number of other mechanisms, such as a fuze 28 or altitude and speed computer means 30.

To accomplish missile arming by the present invention the missile preferably must have attained supersonic speeds during flight and not necessarily during reentry. This requirement is substantially met by all missiles of the supersonic variety which include those that are ground-to-ground, air-to-ground, air-to-air, and ground-to-air. As mentioned above safety and arming may be accomplished at that altitude when the probe temperatures become equal. This can be insured in the ground-to-ground missile and the air-to-ground missile if missile deceleration is present as in most free-falling type missiles. Safety and arming may also be adapted to occur at that altitude giving a definite combination of probe temperatures which include the combination of the temperature differences of the probes

such as T_1 for the relatively low heat capacity probe and T_2 for the relatively high heat capacity probe as illustrated in FIG. 1. This application of aerodynamic heating can be accomplished in all types of ordnance missiles of the supersonic type by conventional temperature response means 24. Similarly, the rates of change of temperatures of the probes such as dI_1/dt and dT_2/dt (FIG. 1) at a particular altitude can be predicted and compared by conventional temperature rate of change response means or circuitry to accomplish missile safety and arming for all type supersonic missiles. One of the most significant contributions of the present invention is the provision of a continuous signal for safety and arming. This is achieved by conventional sensing equipment adapted to permit safety and arming only after the respective probes experience a range of certain preset temperatures or preset rates of change in temperatures, or preset combination of probe temperatures. Thus it will be obvious that arming can take place at any point of a missile trajectory for all supersonic missiles adapting the teachings of the present invention. The probe temperature rate of change response means may be substituted for the probe temperature response means 24 or employed in combination with the latter, as where the altitude and velocity determinations are employed in combination with safety and arming and fuzing, with suitable switching means separating the two rendering one or the other or both responsive to the probes 18 and 20.

The essential requirements for practical and accurate fuzing of a missile that incorporates the present invention are that the missile preferably must have been supersonic and have decelerated during reentry so that a temperature comparison or rate of change comparison of the probes may be made during the terminal portion of flight immediately prior to missile impact. This is met by all free-falling ballistic ground-to-ground missiles and most air-to-ground missiles whose trajectory can be readily predicted. However, for a known or predicted trajectory all types of ordnance supersonic missiles can be effectively fuzed in a similar manner as missile safety and arming which was explained in detail above. In the light of the following disclosure, skilled persons will be able to construct a conventional computer 30 so as to obtain measurements of instantaneous missile speed and altitude.

The temperature variation ΔT of each probe during the time interval Δt (see FIG. 1) is known to those skilled in the art and is

$$\Delta I_1/\Delta t = h/\gamma_1 C_1 \tau_1 (I_1 - T_1) \quad (1)$$

$$\Delta T_2/\Delta t = h/\gamma_2 C_2 \tau_2 (T_2 - T_1), \quad (2)$$

where h is the local effective convective heat transfer coefficient in Btu/sec - °F absolute - ft²;

T_1 is the recovery temperature °F absolute;

γ is the specific weight of probe, lb/ft³;

C is the specific heat of probe, Btu/lb - °F;

τ is the probe thickness, ft;

T is the probe temperature, °F absolute. Since instantaneous values of dT_1/dt , dT_2/dt , T_1 , and T_2 can be measured continuously and γ , C and τ is known for each probe, equation (1) and (2) can be solved continuously for the instantaneous values of h and T_A .

Further, it is known that

$$h = a(\rho v)^b A \text{ and} \quad (3)$$

$$T_A = T_o + Kv^2 \quad (4)$$

where a , b , and K are constants, and ρ , v and T_o are the instantaneous values of ambient air density, missile speed, and ambient air temperature at a selected altitude, respectively. A is a function of T_o and may be expressed as $A(T_o)$.

$$\rho = (h/a A(T_o))^{1/b} 1/V \quad (5)$$

$$v = \sqrt{T_A - T_o/K} \quad (6)$$

$$\rho = (h/a A(T_o))^{1/b} (T_A - T_o/K)^{-1} \quad (7)$$

Curves are predictable for ρ and T_o as functions of altitude y from meteorological data, and may be expressed as

$$\rho = \rho(y) \quad (8a)$$

$$T_o = T_o(y) \quad (8b)$$

Substituting equations (8a) and (8b) into equation (7) will yield

$$\rho(y) = f[h, T_A, T_o(y)] \quad (9)$$

where the instantaneous values of h and T_A are measured by means of equation (1) and (2), as noted above. Equation (9) is now solved by a reiterative process until the solution for y is found. According to equation (9) there is a unique value of y for every pair of h and T_A values. Substitution of T_o into equation (6) will yield the instantaneous value of v . Thus, if h and T_A measurements are made continuously, continuous measurements may be made for y and v . Consequently, the values of y and v may be used to furnish missile intelligence or telemetered by any of the existing conventional techniques.

It will be apparent that the embodiments of the present invention may be suitably combined in many ways. For example, the safety and arming system 26 may be employed in conjunction with the fuzing system 28, and both may be adapted to function along with the altitude and speed measuring system 30. Thus, from the basic contribution to the art by the present invention many ramifications are possible. Further, there are other controllable factors that may contribute to distinctly different probe time-temperature curves aside from probe heat capacities, such as probe surface conditions and surface area exposed to aerodynamic friction. These factors may also be employed to carry out the present teachings of the present invention.

It will be apparent that the embodiments shown are only exemplary and that various modifications can be made in construction and arrangement within the scope of the invention as defined in the appended claims.

I claim:

1. In combination with a ground-to-ground ordnance missile having a predictable trajectory during which the missile attains a supersonic velocity, improved means for obtaining an activating signal at a predetermined altitude prior to impact and after the missile has begun to decelerate, said means comprising in combination: first and second heat-responsive probes mounted to the exterior surface of said missile such that the aerodynamic heating of said probes during missile flight are highly independent of the surface conditions of the missile and missile geometry, each probe being located at the same distance aft of the missile nose so as to be exposed to the same aerodynamic heating conditions during missile flight, said probes being so constructed that said first probe has a heat capacity which is substantially different from the heat capacity of said second probe, said probes thereby having substantially different time-temperature relationships during missile flight, the heat capacities of said probes further being chosen in conjunction with predicted values of missile

velocity, ambient air density and ambient air temperature throughout the missile trajectory so that the instantaneous temperatures of said probes will become equal at said predetermined altitude, and probe-responsive means within said missile connected to said probes for producing an activating signal when the instantaneous temperatures of said probes become equal, said probe-responsive means including an electronic bridge-type circuit for sensing the temperatures of said probes by sensing their resistivities.

2. The invention in accordance with claim 1, wherein each probe has substantially the form of a cylinder with hemispherical ends, the axis of said cylinder being parallel to the missile axis; and wherein said means for mounting said probes comprises a pair of relatively small bosses extending from the missile, each boss adapted to receive a probe at the probe end furthest from the missile nose, said probes and said bosses being insulated from each other so as to minimize heat transfer therebetween.
